[57] CLAIM

The ornamental design for a combined cooler chest and
radio, as shown.

DESCRIPTION

FIG. 1 is a perspective view of a combined cooler chest
and radio showing my new design.

FIG. 2 is a front elevational view thereof.

FIG. 3 is a rear elevational view thereof.

FIG. 4 is a left side elevational view, the right side being
a mirror image thereof.

FIG. 5 is a top plan view thereof, and

FIG. 6 is a bottom plan view thereof.
